UNITED STATES PATENT OFFICE.

ELLIS GREEN, OF MINERAL WELLS, TEXAS, ASSIGNOR OF THREE-FOURTHS TO THE TULSA TOOL COMPANY, OF TULSA, OKLAHOMA, AND ONE-FOURTH TO W. J. NOVAK, OF BRECKENRIDGE, TEXAS.

FORGE AND BIT HEATER.

Application filed June 14, 1923. Serial No. 645,451.

To all whom it may concern:

Be it known that I, ELLIS GREEN, a citizen of the United States, residing at Mineral Wells, in the county of Palo Pinto and State 5 of Texas, have invented certain new and useful Improvements in Forge and Bit Heaters, of which the following is a specification.

My invention relates to liquid fuel and gas 10 burners and particularly to burners for forge and bit heaters; and the object is to equip forges for dressing oil well drill bits and similar purposes and which will distribute the fuel evenly and secure uniform heat 15 and which will trap water, gasoline, or sediment from the fuel or steam and which will be highly efficient in accomplishing such purposes and by which water may be used to soften the bits and to prevent scaling and 20 by which much time may be saved in heating bits. Another advantage is the saving of time in equipping forges and the devices may be readily and quickly adjusted for burning either oil or gas in high or low pressure. 25 Other objects and advantages will be fully explained in the following description and the invention will be more particularly pointed out in the claims.

Reference is had to the accompanying 30 drawings which form a part of this application.

Fig. 1 is a perspective view of the improved burner. Fig. 2 is a rear elevation of the same. Fig. 3 is a plan view of the forge 35 and bit heater, illustrating the connection with a forge. Fig. 4 is a detail view, showing two kinds of burner jets.

Similar characters of reference are used to indicate the same parts throughout the 40 several views.

The burner is provided with a box 1 which is a separator, equalizer, and adjusting device for the various burner nozzles. High pressure or low pressure gas may be used as 45 the heating fuel. A pipe 2 is provided for supplying steam or high pressure gas to the box 1. Means are also provided for supplying low pressure gas to the forge. A pipe 3 is provided for feeding low pressure 50 gas directly to the blow pipes 4. The pipe 2 is provided with a T-pipe connection 5. A pipe 6 for supplying steam is connected to one side of the T-pipe 5 and a pipe 7 for supplying gas is connected to the other side

of the T-pipe and these pipes 6 and 7 are 55 adapted for alternate use, being provided with suitable cocks. For supplying low pressure gas, pipe 3 is connected to the pipe 7. When low pressure gas is to be used, connect pipes 3 and 7 for using or supplying the 60 gas and connect pipes 2 and 6 for supplying steam at the same time, the steam being used to blow the gas into the forge, and, as is well known, the steam furnishes oxygen for increasing the heat. A yoke 8 is provided for 65 adjusting the box 1 closer to or further from the blow pipes 4. Collars 9 may be cast integral with the yoke 8 and the blow pipes 4 are screwed into the collars 9 and project 70 into the forge 10. The box 1 is provided with nozzle jets 11 and 12. When high pressure gas is being used, such nozzles as 11 are used. High pressure gas is fed through the box 1, but low pressure gas is fed direct to the blow pipes 4 being forced in by steam 75 which comes through box 1 and nozzles 11. When oil is to be used, the oil is fed direct to the blow pipes 4 through pipes 13 which are projected into collars 9 and steam is fed through box 1 and nozzles 80 12 for forcing the oil through the blow pipes 4 and also for supplying oxygen for aiding the combustion of the oil. The collars 9 have openings 14 for the pipes 13. When the oil is being used, the receiving ends of the 85 blow pipes must be reduced. For this purpose flanged bushings 15 are screwed into collars 9. When burning gas, no bushings 15 are used. When burning high pressure gas, the box 1 with its nozzles 11 is normally 90 three inches from the ends of the blow pipes 4, but with some grades of gas, more satisfactory results are obtained by changing the position of the box 1, and this is done by sliding the box 1 on the arms 16 of the yoke 8. When the box 1 has been adjusted, it is 95 held in place by set screws 17. When oil is being used, the box 1 should be about one-half inch from the ends of the bushings 15. When using low pressure gas the box 1 with its nozzles 11 should be about one and one-half inches from the collars 9.

Various changes in the construction, proportions, and arrangements of the several parts may be made without departing from 100 my invention.

What I claim, is,—

1. In a forge, a burner comprising blow

- pipes projecting within and without the forge, oil feeding pipes and gas feeding pipes connected to said blow pipes for alternate use, and means for directing a blast of steam into said blow pipes for driving gas or oil through said blow pipes consisting of a control box adjustable relative to said blow pipes and provided with nozzles and steam and gas pipe connections.
- 5 2. In a forge, a burner comprising blow pipes projecting within and without said forge, oil feeding devices and gas feeding devices connected to said blow pipes for selective use, a control box spaced and supported from said blow pipes and provided with nozzles directed towards said blow pipes, and means for supplying steam to said
- 10 box for driving steam to induce oil or gas through said blow pipes.
3. In a forge, a burner comprising blow pipes projecting within and without said forge, oil feeding devices and gas feeding devices connected to said blow pipes for selective use, a control box provided with nozzles directed towards said blow pipes, a 25 yoke mounted on said blow pipes and carrying said control box and means on said control box for positioning the control box on said yoke at different points of adjustment, and means for feeding steam or gas to said 30 control box.

In testimony whereof, I set my hand, this 3rd day of May, 1923.

ELLIS GREEN.
